UNITED STATES PATENT OFFICE.

CHARLES A. LITTLEFIELD, OF FALL RIVER, MASSACHUSETTS, ASSIGNOR TO
ELIAS A. TUTTLE AND JAMES T. MILNE, BOTH OF SAME PLACE.

LOOM FOR CROSS-WEAVING.

SPECIFICATION forming part of Letters Patent No. 380,760, dated April 10, 1888.

Application filed February 19, 1887. Serial No. 228,167. (No model.)

To all whom it may concern:

Be it known that I, CHARLES A. LITTLEFIELD, a citizen of the United States, residing at Fall River, in the county of Bristol and State of Massachusetts, have invented certain new and useful Improvements in Looms for Cross-Weaving; and I do hereby declare the following to be a full, clear, and exact description of the invention, such as will enable others skilled in the art to which it appertains to make and use the same.

The object of my invention is to provide by simple means for the production of a great variety of patterns in cross-woven fabrics. My invention consists in the improved construction of devices hereinafter described and claimed.

In the accompanying drawings, Figure 1 is a view in side elevation of sufficient of a loom to illustrate the application of my invention with my invention applied thereto. Fig. 2 is a sectional view of a detail. Fig. 3 is a view, partly in section, of a portion of the thread-crossing devices. Fig. 4 is an end view of a portion thereof. Fig. 5 is a view of a portion of the pattern-roller. Figs. 6 and 7 are views of one of the washers of the said pattern-roller. Fig. 8 is a view of one of said washers with a number of the lugs hereinafter described applied thereto. Figs. 9 and 10 are views of one of the said lugs. Figs. 11 and 12 are views of one of the needles hereinafter described.

Mounted upon the arch B' of the loom-frame B is a reed, N, having top and bottom or side bars, e e¹⁵, and end pieces, n, to which the side bars are attached by means of screws e¹⁶ e¹⁶, or in any other convenient manner.

N' are the dents of the reed. In practice these dents will be separated and spaced by substantially the same means shown, described, and claimed in my application filed September 20, 1886, Serial No. 214,070.

Pivoted upon the upper side bar of the reed, at w w, are needles D, each having an arrow-shaped head, d', which may be cast or constructed of sheet metal, as desired, and a loop, d, of fine wire secured to said head, as shown.

P is the pattern-roller, the same being composed of a shaft or spindle, m, and a series of sleeves, collars, or washers, m'', which are of

varying widths, according to the desired spacing. Between adjacent sleeves or washers m'' are placed small plates or lugs h, each having the outer projecting portion thereof bent or laterally deflected, as shown, the number of plates in the series between any two sleeves or washers varying in the construction shown from 1 to 12. Any number of lugs may be employed in each series, according to the diameter of the pattern-roller and the requirements of the pattern to be woven, and the said lugs may be placed at any desired points in the length of the roller. Part of the lugs are bent to the right and part are bent to the left, either kind being employed, according to the direction in which it is desired that the needles should be vibrated. Each end of the spindle or shaft m is screw-threaded, and upon each end is a nut, g, serving to firmly clamp together the sleeves or washers and the lugs intermediate the same. On one end of the said spindle or shaft is also a ratchet-wheel, i, having teeth corresponding in number with the lugs in the series around the roller, in the present case twelve.

Loosely mounted on the shaft or spindle m is an arm, R, on which is pivoted a pawl, H, drawn into engagement with wheel i by a spring, H'. A rod, C, having at its lower end a strap encircling the eccentric F upon the crank-shaft f, is pivoted at its upper end to the arm R and serves to communicate motion thereto from the said eccentric.

In operation a portion of warps are passed through the ordinary harness X Y, which is situated behind reed N and between the dents N' of reed N. Another portion of the threads is passed, either singly or in groups, through the half-heddles Z, then through the spaces between dents N', and then through the loops d. The crossing is effected by lowering the ordinary harness-frame controlling the warps which are to be crossed around the warps passed through the loops d. Then, while the lowered warps remain below the ends of said loops d, imparting a partial rotation to the pattern-roller, so as to bring fresh lugs thereon into engagement with the arrow-shaped heads of the needles and to vibrate the latter from one side to the other of the lowered warps, and

then raising the said lowered warps, the movement of the needles causing them to assume positions which permit them to deflect the rising threads to the sides of the threads within 5 loops *d* opposite those on which they were before—that is, assuming the needles to have been moved in one direction or the other by the action of the lugs on the pattern-roller. Heddles *Z*, which are constructed as half- 10 heddles, for the sake of convenience, serve to raise the threads passing through loops *d*, as required in the production of the pattern. 15 The arrangement of the lugs upon the pattern-roller is entirely in accordance with the pattern to be produced. A very great variety 20 of patterns may be produced, inasmuch as every needle is independently acted upon by its series of lugs, and the latter may be arranged in any desired manner around the pattern-roller.

Having described my invention, I claim—

1. The combination, with the shaft or spindle *m*, sleeves or washers *m'*, and nuts *g*, of the lugs *h*, having the laterally-deflected portions, 25 substantially as described.

2. The combination, with the shaft or spindle *m*, sleeves or washers *m'*, nuts *g*, lugs *h*, having the laterally-deflected portions, and means for rotating said shaft or spindle, of the reed and needles pivoted thereto and constructed, 30 as described, to be deflected by the engagement therewith of the said lugs, substantially as described.

3. The combination, with the shaft or spindle *m*, sleeves or washers *m'*, nuts *g*, lugs *h*, having the laterally-deflected portions, and means for rotating said shaft or spindle, of the reed and needles *D*, pivoted thereto, substantially 35 as described.

4. The needle *D*, having the arrow-shaped 40 head, and the loops *d* of fine wire fastened to said head, substantially as described.

In testimony whereof I affix my signature in presence of two witnesses.

CHARLES A. LITTLEFIELD.
